UNITED STATES PATENT OFFICE.

ALBERT W. MORSE, OF FOREST HILLS, NEW YORK, ASSIGNOR TO THE ANTHONY COMPANY, OF LONG ISLAND CITY, NEW YORK, A CORPORATION OF NEW YORK.

BURNER-SUPPORT.

1,391,338.

Specification of Letters Patent. Patented Sept. 20, 1921.

Application filed March 11, 1919. Serial No. 282,048.

To all whom it may concern:

Be it known that I, ALBERT W. MORSE, a citizen of the United States, and a resident of Forest Hills, in the county of Queens and 5 State of New York, have invented certain new and useful Improvements in Burner-Supports, of which the following is a specification.

This invention relates to improvements in 10 burner supports and more especially to supports for oil and gas burners used in conjunction with metallurgical furnaces.

It is an object of the invention to rigidly 15 and correctly apply burners to furnaces.

Another object is to provide adjustable 20 means for varying the distance between burner outlet and furnace wall.

A further object is to obtain accurate 25 alinement of burners with respect to their combustion chamber, and to maintain this accurate and proper alinement during their adjustment with the furnace wall.

Another object is to provide means to shut 30 off the flame inlet opening of the furnace when the burner is not in use for the purpose of retaining all heat possible within the furnace while the burner is not at work.

Other objects of the invention will appear 35 in the following specifications in which a preferred form of my burner support is described.

My invention refers more particularly to 40 application with burners so designed and constructed as to provide minute atomization and thorough mixture at their outlets. In these burners ignition results almost instantaneously. Combustion is rapid. The opening through the furnace wall serves as a combustion chamber which should be care- fully proportioned and exactly sized.

These devices known as mechanically atomizing burners, depend upon high pressure coacting with a spray nozzle to break up the oil into a mist or fog. The most improved 45 type of these burners utilizes air at very low pressure for supporting combustion. This is projected at a suitable angle into the oil mist in proper proportion, instantly forming a highly combustible mixture. The explosive characteristics of the resulting flame demand careful adjustment of the burner with respect to the furnace wall and accurate alinement with respect to the combustion chamber.

In burners of the class described a rigid 55 support fastened to the furnace wall is a mechanical necessity.

To be of maximum efficiency ignition must occur within a limited travel of the vapor mist. The burner characteristics combined 60 with furnace design and method of operating, determine the desired travel. The support therefore must be adjustable to vary the distance between burner outlet and furnace wall to suit different applications. 65

I attain the objects above described by means of the device illustrated in the accompanying drawing in which—

Figure 1 is a vertical longitudinal sectional view of the burner support with part 70 of a burner indicated to illustrate the application and showing a fragmentary section through part of the furnace wall;

Fig. 2 is an end view of the burner support proper, the open position of the shutter being indicated in broken lines; 75

Fig. 3 is a cross sectional view along the plane of line 3—3 in Fig. 1.

Like characters of reference denote similar parts throughout the several views and 80 the following specification.

10 is a burner of the externally mixing class. 11 is an oil discharge nozzle. 12 is an air deflecting plate. The furnace end of the burner 10 is exteriorly threaded at 13 to receive an air deflecting cap 14. All of these parts are common to the externally and mechanically atomizing kind of burners, now known in the art as "Anthony" burners. 85

15 is a part section of the metal shell in- 90 closing the fire bricks, forming the furnace walls proper, of which 16 is a fragmentary section.

17 is a ring threaded internally at 18 to screw onto threaded part 13 of the burner 95 10. Attached to the ring 17, and preferably integral therewith, is a tubular socket 19, the axis of which is substantially parallel to the axis of the burner 10. Tubular socket 19 is tapped to receive a set screw 20 for the purpose set forth hereafter.

21 is a flange provided with a circular opening 22, which flange is fastened to the furnace shell 15 by means of cap screws 23 and 24, respectively. At right angles to the 105 face of the flange 21 is a round stud 25, the axis of which is substantially parallel to the axis of the circular opening 22 through

flange 21. This stud 25 is adapted to slide within the tubular socket 19.

26 is a circular plate or shutter slightly overlapping opening 22 of flange 21 for the purpose of closing the same. 27 is a somewhat thickened extension of plate 26, provided with a bore 28, adapted to fit over a tubular distance piece 29, interposed between a collar 30 of cap screw 23 and the flange 21, 10 to allow shutter 26 to rotate freely about its pivot, set screw 23. 31 is a stop projecting from the face of flange 21, a side 32 of which limits the rotary movement of the shutter 26 when it closes the opening 22, and of which 15 stop a side 33 arrests the travel of the shutter in such a position as to entirely expose opening 22. 34 is a flat lug serving as a handle for manipulating the shutter 26.

35 is a circular opening, smaller in diameter than opening 22, through furnace wall 16, forming a combustion chamber.

The outer end of opening 35 is rounded at 36, while the inner end is of diverging shape at 37, gradually increasing in diameter toward the center of the furnace. Opening 35 is in axial alinement with the burner and therefore also with opening 22, tubular socket 19 and stud 25.

The operation of my device is obvious. Oil 30 is discharged under high pressure through nozzle 11. Air is forced against the oil by means of deflecting plate 12 and cap 14. This breaks up the oil into very small particles outside of the burner and forms a 35 vapor which ignites and is projected by its own pressure into the furnace through combustion chamber 35.

As mentioned *supra*, it is of the utmost necessity that the alinement of the combustion chamber and the burner be accurate, 40 that is, that their center lines coincide, as otherwise the flame is not well distributed within the combustion chamber and may even excessively impinge on one side causing 45 unequal wear, or it may leave a space on another side permitting the drawing in of free air from the atmosphere. This air may enter the furnace unmixed with the carbon elements of the fuel, and under furnace temperatures usually prevalent, attack the material under treatment or its containers and 50 oxidize, burn, scale or otherwise injure or destroy its physical properties. These possibilities must be guarded against, which has been accomplished by this support.

In my device, the burner and the combustion chamber cannot get out of alinement. By sliding the stud 25 within the tabular socket 19, the distance between the burner 60 and furnace may be varied without disturbing this alinement. The set screw 20 is used to permanently clamp the stud 25 in a fixed position.

This method of adjustment greatly improves the performance of the burner, since

the point of ignition which occurs within a limited travel of the vapor mist, can be regulated in a burner equipped with my support, to such a point as to give maximum efficiency to the burner.

As soon as the burner is turned off, the shutter 26 is closed to retain all possible heat within the furnace, without in the least interfering with the adjustment between furnace and burner.

The device is simple and compact, cannot get out of order, and is easily adjustable. Its application to both burner and furnace can be accomplished without any changes in design of burners not equipped with this support.

It is understood that while I have above described my invention as applied to one kind of burner of the mechanically atomizing type, its use and application may be varied, and serve other kinds of burners as well.

Various changes in the form, proportion and minor details of construction may be resorted to without departing from the principle or sacrificing any part of the invention as defined in the appended claims.

I claim—

1. The combination of a burner, a furnace, a burner support, an adjustable connection between the burner and the furnace comprising a pin and socket slidably contacting, and a shutter pivoted on said support.

2. The combination of a burner, a furnace, a combustion chamber, an adjustable support for said burner having a pin and a socket slidably connected, an opening in said support larger than the entrance of said combustion chamber and in alinement therewith, a shutter to open and close said opening, a pivot for said shutter, said pivot serving as a means for securing said support to said furnace.

3. A fuel burner, a furnace, a combustion chamber, a burner support, threaded means on said support to hold the support in axial alinement with the said combustion chamber, and adjustable means comprising a pin and a socket slidably connected to vary the distance between the said burner and combustion chamber.

4. A fuel burner, a furnace, a combustion chamber, a burner support, means on said support to hold the same in axial alinement with the said combustion chamber, means comprising a pin slidably engaged within a socket to vary the distance between the said burner and combustion chamber, and means to secure the latter means in a selected position.

5. A fuel burner, a furnace, a combustion chamber in said furnace centrally alined with said burner, a support for securing said burner in alined position, said support being provided with adjustable means com-

prising a pin and a socket for varying the point of fuel ignition within said combustion chamber without disturbing said alinement.

6. In a burner support, a bracket for rigidly attaching to a furnace, a threaded collar for securely attaching to burner, a pin projecting from the said bracket, a tubular socket projecting from the said threaded collar and adapted to slide over the said pin, 10 a set screw for fastening said pin in any de-

sired position of adjustment, and a pivoted shutter attached to said bracket.

In testimony whereof I have hereunto set my hand and seal in presence of two subscribing witnesses.

ALBERT W. MORSE. [L. s.]
